UNITED STATES PATENT OFFICE

1,928,680

PUNCHING MACHINE

Casimir L. Werk, Jr., Cincinnati, Ohio

Application July 10, 1930. Serial No. 466,920

4 Claims. (Cl. 164—112)

It is the object of my invention to provide a novel office machine for punching paper or the like for use for instance in an identification system. Instancing such identification system it may be assumed that a letter of credit is issued to a certain person for a given amount and that the letter of credit has holes therein, which holes are located in the letter of credit in selective positions to correspond with the identifying data and a key therefor furnished to the probable payers of the letter of credit.

It is the object of my invention, further, to provide a novel arrangement of movable frame comprising punch mounting means and a die plate and a coacting selector-frame comprising selector means complementary to the punches; further, to provide novel means for mounting and moving the movable frame; and, further, to provide novel means for causing coaction between the respective selector means and the respective punches; and my invention consists in the novel parts, and in the novel construction, arrangement and combinations of parts herein-after disclosed and claimed.

25 The invention will be further readily understood from the following description and claims, and from the drawings, in which latter:

Fig. 1 is a plan view of my improved device, partly broken away.

30 Fig. 2 is a front elevation of the same.
Fig. 3 is a horizontal section of my improved device, taken in the plane of the line 3-3 of Fig. 2.

Fig. 4 is a side elevation of my improved device.

Fig. 5 is a vertical section of a detail of the same, taken in the plane of the line 5-5 of Fig. 3, and partly broken away.

Fig. 6 is a vertical section of my improved device, taken in the plane of the line 6—6 of Fig. 7.

Fig. 7 is a vertical section of my improved device, taken in the plane of the line 7-7 of Fig. 6, and partly broken away.

Fig. 8 is a rear elevation of a detail of the 45 clearing key in its connections, partly broken

Fig. 9 is a perspective view of a detail of one

of the selector keys and its connections, partly broken away.

50 Fig. 10 is a horizontal section of my improved device, taken in the plane of the line 10—10 of Fig. 7 with the cover removed.

Fig. 11 is a sectional detail view of one of the long posts and its connections, taken on the line 55 11-11 of Fig. 1, partly broken away; and.

Fig. 12 is a sectional detail view of the short post and its connections, taken on the line 12—12 of Fig. 1, and partly broken away.

The frame of my improved device comprises a base 11 from which posts 12, 13, extend upwardly. 60 The posts are fixed in bearings 14 in the base.

The base is preferably in the form of a trough comprising a bottom 15 and a marginal flange 16. The parts for operating the punch are located in the trough. The trough receives any drippings of oil, dirt or punchings due to the operation of the machine. The bottom of the trough is provided with an opening 17, in which a pan 18 is received, the pan being provided with lugs 19 having holes received about screws 20 in the bottom, nuts 21 being threaded about the screws and clamping the lugs to the base for clamping the pan in position. The pan is preferably sufficiently large in area to extend under all of the punches for receiving the punchings therefrom. 70 75

A cushioning foot 25 is located under each of the corners of the base, being for instance a block of rubber secured to the corner as by means of a screw 26, shown threaded in the lower end of the post.

A frame 31 has bearings 32 at its respective corners received about the posts 12, 13, and is slideable up and down on said posts. This frame is formed as a rigid structure, being provided with outer marginal depending flanges 33, and cross-ribs 34.

A die-plate 35 is fixed to this frame, as by means of screws 36. The die-plate is provided with a series of rows of punch holes 37 complementary to the punches hereinafter described, and with a master punch hole 38, complementary to the master punch hereinafter described.

In the present exemplification the die-plate is shown as the movable one of the complementary pair of punching parts, the punch being exemplified as the relatively stationary member of the cutting pair, although either member of the cutting pair, or both members of the cutting pair, may be movable, and the positions of the punches and the dies may be reversed, without departing from the spirit of my invention. 95 100

The means exemplified for operating the die-plate comprises a pair of rocker-rods 41, 42, journaled in bearings 43, in the base. Arms 45, 46, are fixed to the respective rocker-rods. The arms are 105 integral with hubs 47, 48, fixed to said rocker-rods. The swinging ends of the arms are operatively connected with each other, as by forming the end of one of the arms as a fork 49 having a pin 50 therein, the end of the other arm being provided 110

with a slot 51, the walls of which are located in the fork about the pin, so that movement of one of the arms is imparted to the other.

Arms 54, 55, are fixed to the rocker-rods, being shown integral with the hubs 47, 48, and arms 56, 57, extend integrally from hubs 58, 59, fixed to the opposite ends of the rocker-rods. The arms 54, 55, 56, 57, are provided with slots 61, 62, extending radially from the pivots of said arms, that is, from the rocker-rods. Pins 63, 64, are fixed in the punch frame and are located in said slots. Rocking of the rocker-rods causes up and down rocking movements of the arms, thereby moving the punch frame up or down on the upright posts 12, 13, guided by the bearings 32 about said posts. Cushion washers 65 surround the posts.

Suitable means may be provided for operating the rocker-rods, exemplified as an operating arm 67 having a hub 68 fixed to one of the rocker-rods, 20 and a handle 69 for manually manipulating the same.

The die-plate 35 is provided with ledges 66 overhanging the marginal flanges 16 of the base for preventing pinching of the fingers of the operator 25 in the slot between said die-plate and marginal flange.

A punch-frame 71 has a series of punches 72 and a master punch 73 therein. The series of punches may be termed junior punches. They are arranged in rows, preferably of ten punches each, a suitable number of rows being provided, twelve of these being shown. The punches are arranged to have reciprocating movement relative to the frame.

The punch-frame comprises a skeleton frame 74, a plate 75 at the top of the latter secured thereto, as by screws 76, and a plate 77 at the bottom of the frame secured thereto as by screws 78. The plates are provided with registering holes 79, 80. The punches of the series of punches are guided in the registering holes 79, 80. The master punch is guided in registering holes 81, 82, in said plates. The punches are in the form of stems guided in said holes. They have cutting edges at their lower ends which coact with the cutting edges of the punch-holes in the die-plate for cutting the sheet. The master punch is exemplified as cutting a slot and the series of punches, or junior punches, as cutting smaller holes.

There is a sheet-receiving space 85 between the die-plate 35 and the plate 77, formed for instance by strips 86, 87, the inner margins of which form gaging edges for positioning the sheet between said plates, so as to cause registry of the sheet in correct relation in said space for punching the holes therein in correct positions. The plates 35, 75, 77, the gage-strips 86, 87, and the frames 31, 71, may be rigidly secured together by screws 88 for causing all of these parts to move together when operating the operating handle. The post 12 is a short post, being located wholly under the space 85.

The junior punches are retracted in the punch-frame, as by helical springs 91 surrounding the same and located between the plate 77 and a washer 92 positioned on the punch by a pin 93. The pin acts as a stop against the plate 75 to limit upward movement of the punch.

The master punch is retracted in the punch frame, as by a spring 94 received about the master punch between the plate 77 and a washer 95 located on the master punch by a pin 96. The pin engages the plate 75 and limits upward movement of the master-punch.

Selector means are provided for selecting which

of the punches in the series of punches are to be operated, and, in the present exemplification tripping or clearing mechanism is provided in each of the rows of selector parts, so that when one of the selector parts in any row is operated, the balance of the selector parts therein are released. The selector parts are arranged in rows complementary to the punches in the respective rows of punches.

The selector parts are exemplified as bars 101. These bars are arranged to be placed in coactive relations with the respective punches of the series of punches. They are shown mounted in a selector frame 102 provided with bearings 103 at three of its corners received about the upper ends of the posts 13 and fixed to said posts as by set-screws 104. Guide bars 105, 106, are secured respectively to the upper face and to the lower face of the frame 102, as by means of screws 107 passing through registering apertures in said bars and in the frame, nuts 108 being threaded over said screws for clamping the parts together.

The bars 105, 106, are provided with notches 111, 112, in which the shanks of the bars 101 reciprocate. The walls of said notches and the edge 90 of the adjacent bar form the guides for said shanks.

Helical springs 115 are received about the bars 101, the lower ends of said helical springs bearing upon the bars 106, their upper ends being resisted by washers 116 surrounding said bars, pins 117 received through said bars locate said washers, and limit upward movements of the bars by contact with the lower faces of the bars 105.

The bars 101 are provided with projections 118 having shoulders 119 received under pins 120 on slide-bars 121, the projections having inclined edges 122 for moving the pins laterally, in order that they may be retracted above the shoulders 119 when the bars 101 have been sufficiently 115 depressed.

The slide bars 121 are reciprocable in bearings formed by the depending ends 123 of the bars 106, these depending ends being provided with notches 124 forming lower lugs 125 on which the lower edges of the slide bars rest, the upper edges of the slide bars being guided by the bodies of the bars 105, and the side faces of said slide bars being guided by the bottoms of the notches 124 and the edge of the depending end 123 adjacent thereto. The structure forms slots in which the slide bars move. Each of the slide bars is provided with a positioning pin 120 for each of the control bars 101 in the row of control bars affected thereby.

Each of the slide bars has its end bent to form a lug 131, in which there is a pin 132, which is received in a hole 133 in the depending lug 123 of the bar 106. A helical spring 134 surrounds said pin and normally urges the slide bar in one direction for placing the pins thereon against one of the edges of the bar 101, and normally urges the pin into position above the shoulder 119 thereon when the control bar is depressed into coactive relation with its corresponding punch.

The depressing of any one of the selector bars 101 moves the slide-bar laterally so as to move all of the pins thereon laterally out of engagement with any of the shoulders 119 which may have been thereunder, for releasing all of said selector bars which may have been previously depressed in said row, the slide bar immediately retracting for locating one of its pins above the shoulder of the selector bar which is momentarily depressed, for retaining said depressed selector bar in depressed position, and insuring that only

one of said selector bars in any one row thereof may remain in depressed position, it being assumed that only one of said selector bars is depressed at a time.

5 Any selector bar in each of the rows may be thus depressed and remain in depressed position, the depressed selector bars being those which control the operation of the punches for producing the identifying holes in the letter of credit 10 or other sheet placed in the machine.

One of the slide bars 121 is provided with a contact part 135 arranged to contact the master punch and to be in contact position throughout all punching operations so that the master punch 15 will punch at each punching operation.

A full-clearance device is provided, instanced as comprising a rocker-bar 141 provided at its respective ends with pivot lugs 142 and pivoted to the frame 102 by screws 143. Each of the 20 slide bars is provided with a recess 144 in which the pivot bar is received, for moving all of the slide bars into release position, so as to release all of the control or selector parts for the series of punches. The end walls 145 of the recesses 144 25 make contact with the rocker-bar so that rocking movement of the rocker-bar simultaneously moves all of the slide bars. The end walls 145 form stops for the retracting movements of the slide bars.

30 An arm 146 is fixed to the rocker bar, as by a screw 140, a spring 147 being located between its outer end and a pin 148 in the frame 102, and normally retracting the rocker-bar. An arm 149 extends from the rocker-bar and has a clearance- 35 key 150 thereon.

A cover 154 is provided, the cover being secured at its respective corners. The cover has depending walls 155. It is provided with a slot 156 at its front and at one of its sides registering with 40 the space 85 for the reception of the sheet to be punched. The lower edge of the cover is at three of its corners and one of its sides and ends provided with a flange 157 merging with the corresponding corners, side and rear wall of the upwardly extending flanges of the base and preferably resting on said base.

The cover is at its four corners secured to the frames, as by means of screws 158. One of said screws is threaded into the overhanging corner 50 of the selector frame, above the outer free corner of the space 85. The screws at the other corners are threaded into the posts 12. The screws clamp the cover at its four corners and strengthen the overhanging support of the selector frame so as to aid in resistance to stresses in 55 the punching operations.

The cover is provided with an opening 161 for exposing the key-board 162 of the machine. Keys 163 are fixed to the outer ends of the selector bars. There are a number of rows of these keys. Each of the rows preferably comprises ten keys, respectively provided with the digits from 1 to 0 inclusive and consecutively arranged from left to right. Twelve rows of such keys are 60 shown similarly arranged. The arrangement of the rows and the sequence of the digits is immaterial, but they are preferably consecutively arranged in the respective rows, all the rows being alike for ready and speedy selection.

70 The arm 149 for the clearance lever extends through a slot 164 in the top of the cover and forms a clearance key for all of the keys of the series of keys for clearing the selector mechanism.

75 The punch frame and connected parts are normally retracted, as by the weight of the parts.

My improved device is intended primarily for use in an identification system in which the identifying means are obtained through selectively placed marks on a sheet, for instance a letter of credit.

80 The master punch locates a slot adapted to be arranged in registry with a master indication on an interpreting sheet of the identifying system, the master indication corresponding with a secretly selected item appearing on the letter of credit, for instance the amount thereof, which is suitably interpreted by a code mark or designation on the interpreting sheet.

85 A key in each of the rows of keys is depressed, the selection being made according to the indications of a secret interpreting sheet. Each of the keys depressed places a selector part into coactive position with a corresponding punch. The depression of any key depresses the projection 118 on the selector part for moving one of the pins 120 and thereby sliding the corresponding slide-bar 121 and releasing any other selector part in its row, for automatically retracting the selector parts in the row except the selector part, the key of which has just been depressed.

90 When the proper keys have been depressed, the sheet representing the letter of credit is slipped through the slot 156 and into the space 85, the rear edge of the sheet being brought into registry with the rear gage 87 and the side of the sheet being brought into registry with the side gage 86. The operating arm 67 is thereupon depressed, which, through the intervention of the rocker-rods 41, 42, and the arms operated thereby, raises the punch frame, including the die 95 plate 35, the punch frame 71 and all of the series of punches thereon which have no obstructing selector parts 101 in coactive relation therewith.

100 Those punches of the series of punches which are in line with selector parts 101 placed in obstructing relation, are prevented from moving with the punch frame, the punch frame moving with relation thereto and the die-plate forcing the sheet upon the punches thus obstructed, for 105 piercing the sheet and providing the same with holes corresponding in position or relation to the relation of the punches which have been obstructed by the selector parts complementary to the actuated keys.

110 The master die opening in the die-plate also 115 moves upon the master punch for providing the sheet with a master slot or hole. The punches are normally retracted into the wall of the space 85 so that the sheet may be readily inserted into and removed from said space.

120 Upon retraction of the operating arm, the die plate and punch frame are retracted for freeing the sheet from the punches. The sheet will have been provided with a master hole and a series of junior holes in proper interpreting relation, the interpretation, however, being secret and only possible by a holder of the interpreting code and interpreting sheet of the system.

125 Having thus fully described my invention, what I claim as new, and desire to secure by Letters 135 Patent, is:

1. In a machine of the character described, the combination of a base, a selector frame thereabove in rigid relation thereto, keys arranged in rows above said selector frame, a series of rows of selector parts supported by said selector frame and respectively actuated by said keys, a punch frame between said base and said selector frame, a series of punches therein arranged in rows complementary to said selector parts, a die plate pro-

vided with punch holes complementary to said punches, means for normally retracting said respective punches, an operating rocker rod, a second rocker rod parallel therewith and spaced 5 therefrom, said rocker rods journaled in said base, arms fixed to said rocker rods projecting toward each other and having an operating joint therebetween for operatively rockingly connecting said rocker rods, operated arms on the respective ends 10 of each of said rocker rods, and operative connections between each of said last-named arms and said punch frame, whereby to move said punch-frame toward said selector-frame for causing the reception of said punches complementary 15 to key actuated ones of said selector parts in complementary die holes in said die plate.

2. In a machine of the character described, the combination of a base, a selector frame thereabove in rigid relation thereto, keys arranged in 20 rows above said selector frame, a series of rows of selector parts supported by said selector frame and respectively actuated by said keys, a punch frame between said base and said selector frame, a series of punches therein arranged in rows 25 complementary to said selector parts, a die plate provided with punch holes complementary to said punches, said punch frame comprising a sheet receiving space between said punches and said die plate, means for normally retracting said re- 30 spective punches, an operating rocker rod, a second rocker rod parallel therewith and spaced therefrom, said rocker rods journaled in said base, arms fixed to said rocker rods projecting toward each other and having an operating joint there- 35 between for operatively rockingly connecting said rocker rods, operated arms on the respective ends of each of said rocker rods, and operative connections between each of said last-named arms and said punch frame, whereby to cause relative 40 movement between said selector frame and said punch frame for causing the reception of said punches complementary to key actuated ones of said selector parts through said sheet receiving space into complementary die holes in said die 45 plate for piercing a sheet in said sheet-receiving space.

3. In a device of the character described, the combination of a base, a movable frame comprising a punch-frame, a die-plate and a guide-frame 50 all rigidly connected and having a sheet-space

between said punch-frame and said die-plate, said guide-frame located below said die-plate, said sheet-space open at one of the corners of said punch-frame and die-plate, punches substantially throughout the area of said punch-frame, posts 80 rigidly secured to the four corners of said base, the post at said one of said corners being short, said movable frame provided with guides on the others of said posts, said guide-frame provided with a guide on said short post, said short post and said guide thereon located wholly below said sheet-space, a selector-frame above said punch-frame fixed to said others of said posts, and selector-bars on said selector-frame substantially 85 throughout the area of said selector-frame, said respective selector-bars cooperating with said re- 90 spective punches, and arranged for resisting the punching stresses of said punches substantially throughout the area of said punch-frame and adjacent to said open corner of said sheet-space. 95

4. In a device of the character described, the combination of a base, a movable frame comprising a punch-frame, a die-plate and a guide-frame all rigidly connected and having a sheet-space be- 100 tween said punch-frame and said die-plate, said guide-frame located below said die-plate, said sheet-space open at one of the corners of said punch-frame and die-plate, punches substantially throughout the area of said punch-frame, posts rigidly secured to the four corners of said base, said movable frame provided with guides on the others of said posts, the post at said one of said corners being short, said guide-frame provided with a guide on said short post, said short post and said guide thereon located wholly below said sheet-space, a selector-frame above said punch-frame fixed to said others of said posts, selector-bars on said selector-frame substantially through- 105 out the area of said selector-frame, said respective selector-bars cooperating with said re- 110 spective punches, a cover having depending flanges received about said selector-frame, and securing means fixing said cover to said connected posts and selector frame, and having resistant con- 115 nection with said selector-frame at said one of said corners, and arranged for resisting the punching stresses of said punches substantially throughout the area of said punch-frame and ad- 120 jacent to said open corner of said sheet-space. 120
